UNITED STATES PATENT OFFICE.

GEORGE MACBETH AND MALCOLM MACBETH, OF LIVERPOOL, ENGLAND.

CASH-REGISTER.

1,272,978.

Specification of Letters Patent. Patented July 16, 1918.

Original application filed January 8, 1915, Serial No. 1,263. Divided and this application filed October 2, 1916, Serial No. 123,425.

To all whom it may concern:

Be it known that we, GEORGE MACBETH and MALCOLM MACBETH, subjects of the King of England, residing at 4 Streatham 5 avenue, Sefton Park, Liverpool, in the county of Lancaster, England, have invented new and useful Improvements in or Connected with Cash-Registers, of which the following is a specification.

10 This invention has reference to apparatus used in connection with the selling of goods and the indicating and recording of cash received for same generally called "cash registers", wherein the amounts of transactions are recorded on a recording ribbon or strip in connection with date or date and time records, and a ticket is printed and delivered to the purchaser.

The invention described in this application is divided from my co-pending application filed Jan. 8, 1915, Serial No. 1263, and is illustrated in the annexed drawings, in connection with which it will be described, while the features which are claimed as 25 novel are those set out in the claiming clauses concluding the specification, the invention under the respective clauses being the several features or parts included in them, in combination, and not individually 30 or separately.

In the drawings, Figure 1 is a cross section showing a register according to this invention; Fig. 2 is a front view and Fig. 3 is a plan in section.

35 Figs. 4 and 5 are elevation and plan showing the time and date recording mechanism in detail; and Figs. 6 and 7 are elevation and plan of the ticket printing and delivering mechanism in detail.

40 Referring to the drawings, 1 are the actuating keys of the machine; 2 is a hand operated handle or lever co-operating with the keys 1. The handle 2 is fixed on the spindle 3 supported by the members 4 of the main 45 frame, and by the inner members 5.

The date and amount recording or printing rollers and the printing rollers of the ticket printing and delivering mechanism are mounted on a shaft 9, supported in the 50 frames of the machine.

The keys 1 operate in connection with a gate device 20, which has vertical movement on the rods 25 through the bosses 24 thereon.

The record tape printing mechanism is fixed

to the outside—the right hand side in the 55 case shown—of one of the frames 4 of the machine. This tape is designated 64 and is operated from the shaft 3, on which is fixed a plate lever device 65 having a pawl 66 on it, which engages and operates the ratchet 60 wheel 67, revolving on a shaft 68, having fixed upon it a drum 69 on which the record strip 64 is wound, so that as the shaft 3 is moved to and fro, the paper 64 is wound on the drum 69, and off the store 65 drum 70, passing on its way over the vertically moving presser block 71, which presses it against the pence and shillings type wheels which are designated 72 and 73 respectively.

The presser bar 71 is operated by a lever 70 74 on the inside of the frame 4; and is mounted loosely on the shaft 3, and it is adapted to be raised at the end of the outward pull of the lever 2 by a tappet 75 on the plate lever 65 coming in contact with the 75 part 76 on the lever 74, which presses it up and so elevates the block 71, and presses the ribbon 64 on to the type wheels.

The pence and shillings type wheels 72 and 73 are provided on both sides of the 80 machine; and as seen in Figs. 4 to 7, are mounted respectively on the spindles 9 and sleeves 77.

The pence rack 43 will engage with the wheel 48 on the spindle 9, and so revolve the 85 shaft 9; while the sleeve shafts 77 are revolved from the wheel 49 fixed on it (see Fig. 3), engaging with the shillings rack 43, hereinafter described; and this wheel 49 meshes with and drives another wheel 78, 90 fixed on a short lay shaft 79, having on its opposite end another toothed wheel 80, which meshes with a wheel 81¹ on the other sleeve 77; so that these sleeves 77 are continued both to the paper strip recording 95 mechanism, and also the ticket printing delivering mechanism at the other, the left hand side of the machine, and are both operated.

The zero position of the type wheels 72 100 and 73 is always such that they will be inked by the inking rollers 81 during the preliminary rotation by the movement of the racks 43, before they are moved to a definite position by the gate; so that in each action, when 105 the type rollers are revolved, they will always be freshly inked in moving over the block 71; and this preliminary movement is

effected by the spring 47 which pulls up the rack 43, when the trigger 42 is removed from it; this movement being allowed by the slotted parts 46 of the racks—all of 5 which parts are hereinafter described.

With regard to the ticket printing and delivering mechanism (see in Figs. 6 and 7), and the tickets to be delivered to customers, this mechanism is fixed to the frame 4 at the 10 opposite side of the machine to the tape printing mechanism. The tickets are arranged to be marked and receive the amount paid on each transaction, the date of such transaction, and also if desired other data; 15 and they are adapted to be cut off from a paper ribbon 83, coiled on a suitable storage roller.

To this end the pence and shillings wheels 72 and 73, which will have been moved by 20 or from the gate and racks 43 by the first part of the movement of the handle 2, will be previously inked by the inking rollers 81, similar to those above described, as they are moved over from the zero position to 25 their active position; and the date wheels 84 are also and similarly inked by roller 81.

The presser block 85 has two raised parts directly under the rollers 72, 73, and 84 which presses different parts of the strip 83 30 on to these type wheels, and prints them, and the actuation of the block 85 is effected by a lever 86 loose on the shaft 3, and actuated by an adjustable tappet 87 on an arm 88, fixed on the shaft 3; the free end of the 35 lever 86 striking the part 89 of the block 85, and when so struck presses it up. The return action of the block is effected by a spring 82.

The date wheels 84 which will be set each 40 day, say through the milled screw heads 91 through any suitable known means, will be reciprocated over their ink roller 81, so that an inked part comes over the block 85, by a bar 92 on the lever 86, the upper end of 45 which engages with the upwardly spring pressed arm 93 on the spindle of the wheels 84, and so turns them; free movement between the upper end of the bar 92 and the arm 93, being allowed, so that the rollers 50 shall not be moved when the block 85 is being lifted by the lever 86.

During the first operation of movement of the shaft 3 and arm 88, a rack 94 will be moved up, and this rack engages with a 55 toothed wheel 95 on the spindle 96, and revolves this wheel past the pawl 97 on the roller 98, over which the ribbon 83 passes, which is pressed down on to the roller 98 by a roller 99, carried on the arm 100, supported on a pivot 101, and pressed down by a spring 102. Thus in this free wheel action the roller 98 is not revolved, during 60 which time the print is being effected from the rollers 72, 73, and 84. In the return 65 stroke of the rack 94, on the return action

of the lever 2, the part of the wheel 95 engages with the pawl 97, and revolves this roller 98, at which time the presser 85 will be away from the type wheels, and so the front portion of the ticket will be fed forward over the edges of a lower guillotine knife 103, on to the table 104, and it will feed the required length of ribbon on to this table, and when this is done, and the rollers 98 and 99 have been stopped, the upper 70 guillotine knife 105, which will have been held up, is released, and it cuts off the paper piece, so that the printed portion constitutes a ticket, and can be taken away, being a 75 receipt for the money. 80

The cutting off blade 105 is held up by the upper end of a bell crank detent 106, pivoted on the lower end of the fixed guillotine blade 103; this detent being removed from this holding up position at the required 85 time, by the part 107, on the rack plate 94 coming on to the other part of the detent, and knocking it away from 105. The blade is pulled down by a spring 109.

The plate 105 is pressed up by a cam 110 90 on shaft 3, which acts on a lever 184 connected with the plate of the blade 105.

With regard to the money printing or impression recording apparatus, this may also be adapted to be used for recording the 95 time by users of the instrument, say when coming to or leaving the place of business, or other act, in which the instrument is used, so their arrival or departure as to time, or other important memoranda, may be entered 100 on the record.

The handle 2 will be used and operated to effect this time registering as in other registering actions; but instead of or in addition to the hand lever 2, for operating the 105 mechanism, it may be operated by a rotary crank or handle 119, as shown in Fig. 4.

The machine shown is adapted for recording both pence and shillings and has a facsimile arrangement and duplication of parts 110 on each side of the machine.

With regard to the operation of the parts above described, and their general control any of the keys 1, when moved in by hand, act upon a swinging locking and releasing 115 means, consisting of plates 26 fixed on vertical plates 27, which carry at their upper ends, a plate 28, which controls the gate 20 so far as vertical movement is concerned, and constitutes the vertical locking means. 120 Namely, when the key is operated, it acts upon one of the bars 26 or 28, as the case may be, and presses this locking device or means back, and so moves the upper plate 28 back and out of the way; that is, out of 125 the plane of the upper bar 22 of the gate, which it normally stands above.

The plates 26, 28 and the bars 27 constitute a species of swinging frame, which is supported from a fixed part of the machine 130

by suspension links 29, so that it is capable of being moved horizontally, and when it is so moved by a key, so that the bar 28 is moved away back out of the plane of a gate 5 bar 22, it allows it to move up, which is effected by a spring 30 as hereinafter described and according to which key is moved in, so will be the degree of movement vertically of the gate permitted and this is 10 governed by the diagonal inclined bars 22 of the gate.

Thus according to which key is moved into the path of the diagonal gate bars 22, so will be the upward amount of movement 15 of the gate 20, and type wheel racks 43, the distance from the axes of the keys of the different rows and the active edges of the different diagonal bars 22 vertically, being different in the rows of keys, starting at 20 the smallest at one end of the top row, and finishing with the largest at the opposite end of the lowermost row.

The gate, when operated, and after each actuation, is moved down to its normal or 25 zero position (shown in the drawings) by a handle lever 2, and is held there by the plate 28 of the swinging frame 26, 27 by its lower edge standing above the upper edge of the upper diagonal gate bar 22.

30 The gate device, no matter what key 1 is actuated, acts upon a part of the swinging frame (26, 27, 28) and frees the gate and the type operating racks 43, so that they can rise vertically.

35 The swinging frame 26, 27, 28, is supported by the links 29, through horizontal backwardly projecting bars 32, fixed to the back of the frame, which their lower ends are hinged to.

40 Connected with the locking and releasing frame device 26, 27, 28 there is an arm or bar 33, the inner end of which is bifurcated or in the form of a fork, which is supported by the hinge rod 34 connecting the links 29 45 on the bars 32.

This bar 33, on its forked end, has a projection 35 adapted to act upon a lever or arm 36 fixed on the transverse shaft 11, and normally pressed against it by a spring 37, 50 which pulls on a projecting arm or lever 38 connected with one of the arms 36.

With regard to the handle 2, this is only moved after the keys 1 have been actuated, and when the machine is in the normal condition, the handle is engaged and held by 55 a catch or detent 39, loosely mounted on the shaft 11, its end engaging with the catch 40 on the handle. But when a key is pressed in and the releasing and locking frame 26, 27, 28 and parts above described, are actuated, the catch 39 is actuated and frees the hand operated lever 2.

In the construction shown, this freeing action is effected by an arm 41 fixed on the 65 shaft 11, which acts on the arm of the catch

39 (through a bell crank trigger 42 herein-after described) and operates it: the shaft 11 being as stated, actuated, that is, rotated when the key is moved in.

The hand lever 2 is now free to be moved. 70

Simultaneously, with the movement of the catch 39, by the arm 41, the trigger 42 will be moved. This trigger acts as a detent to, and works in connection with the two rack bars 43, one on each side of the machine, 75 which operate in connection with the gates 20, so that when the trigger 42 is actuated as just described it moves out of the path of and frees the racks 43, and so the gates 20—which are connected with the racks 43, 80 by bars 44 and slotted ends 45 on them, through which pins 46, passing through the slots—are freed, can then be moved up by the spring 30 when the handle 2 is actuated, but not before. 85

The type wheels operating rack bars 43 which operate in connection with and are controlled by the trigger pawls 42, and with the gates are capable of relatively vertical movement to a certain extent with the gate 90 this being provided by the slots 45 and pins 46 above described. That is, the bars are free to slide more or less vertically in relation to the gate, this independent or free motion being provided for purposes herein- 95 after described.

The racks 43 are normally pulled upward by springs 47.

These racks 43 are moved by the gate 20 and operate pinions 48 and 49 on the spindle 100 9, which operate the paper tape and ticket printing or marking means, consisting of the type wheels 72, 73 containing type representing money, as above described.

The limited movement of the rack parts 105 43 is primarily intended to cause a preliminary inking of the type wheels as above referred to, prior to such type being impressed upon the recording type and ticket; namely, when these rack bars are released by the 110 triggers 42, the slots in the parts 45 allow of them being moved up over the pins 46 by the springs 47 to the end of the slots, and so they actuate the toothed wheel 48 and 49 and shaft 9, on which the type wheels 115 are fixed.

With reference to the means for actuating the gate and type wheel operating racks 43 as above described, this is effected through the spring 30, but this spring can only act 120 upon the gate when it is freed, it being normally unable to act by parts, hereinafter described, between it and the gate, which hold it down in its lowermost position.

This holding means consists of a weight 125 50 fixed on to the transverse shaft 8, on the back of the machine, and having a forwardly projecting part 57, connected by the link 52 at its front end, with the projection part 53 of or connected with the hand 130

- lever 2. The weight 50 of course will exert greater force than the spring 30, instead of a weight however being used a spring stronger than the spring 30 could be used.
- 5 The spring 30 is connected to a lever 54 loosely mounted on the shaft 8 and extending toward the front of the machine, where it is connected by a link 55 with the bottom part 56 of the gate 20 and the weight 50
- 10 rests and acts on the lever 54 through an adjustable pin 58 on the end of which the dotted shaded part (see Fig. 1) of the weight 50 rests. Thus when the weight 50 is resting on this pin 58, it keeps the lever 54
- 15 down, and the spring 30 in tension, and also holds the gate 20 down, but when the lever 2 is pulled forward, the weight 50 will be lifted off the pin 58, and so the lever 54 and gate 20 will be freed, and the spring 30 can
- 20 lift them up; and this will take place when one of the keys 1, is pressed in, and the gate freed by the swinging frame 26, 27, 28.
- The movement of the weight 50 by the hand lever 2 will be much greater than the
- 25 upward movement of the gate 20, and the lever 54, but this extra movement does not affect the gate's action.
- The function and effect of the weight 50 is to govern or regulate the upward move-
- 30 ment of the gate 20.
- With regard to the mode of operating the hand lever 2, it is the duty of the user to move it to its full stroke or extent. Thus in all cases, when the gate reaches the end of
- 35 its up-stroke whether a portion of the total proper stroke or the whole of it, the weight 50 moves away from the spring pressed arm 54, whose motion upward is limited through the limited movement of the gate.
- 40 In the latter portion of the outward stroke of the hand lever 2, a part on it, namely the boss of the double bell crank levers 59 arranged on each side of and pivoted on the part 53, strikes the lower end of the project-
- 45 ing bar 33 of the swing frame 26, 27 28 and lifts it, and so lifts the projection 35 above the end of the arm 36 so that the spring 37 acting on the arm 38, can turn the shaft 11, and so cause the arm 41 to move down, the
- 50 catch 39 thereby being free to move down also into the engaging position.
- In this movement of the arm 41, it moves away from the trigger or detent 42, the lower end of which will be pressed against the face
- 55 of the rack bars 43, so that when a rack 43 moves down, till the upper end of the rack proper is below the level of the lower end of the trigger 42, it—the trigger—can be moved by a spring 60 over to the locking
- 60 or holding position as seen in Fig. 1, whereupon the upper arm of the detent 42 will come on to the nose of the lever 41, when the catch 39 can drop down into the engaging position.
- 65 By this outward movement of the hand

lever 2 as stated, the gate 20 will have been freed so as to be able to rise; and when this latter action takes place, the type rollers 72 73 for printing the paper ribbon and ticket through the racks 43, will be actuated, 70 and set to the position corresponding with the sum of money taken and registered.

The next operation is the return action of the hand lever 2. In the first position of this return stroke, the lower outer end of the double hinged trigger 59 (which is normally pulled up by a spring 61) acts upon the type wheels actuating rack parts 43, namely, this trigger acts upon a block 62 on each of the bottoms of the rack bars 43, and moves these 80 rack bars down, and in this operation the weight 50 will also have been lowered by the lever 2, and will have come in contact with the pin 58 on the arm 54, and so moved it down; and as this arm or lever 54 moves 85 down, the gate 20 is pulled down by it. So the rack bars 43, and the gate 20, move down together, but their movement is effected by independent means.

The lowermost position of the lever 54 is 90 governed by a stop 63 on the bottom of the machine, with which it comes in contact.

Near the end of the stroke of the lever 2 the trigger 59 will move off the blocks 62 and out of their paths, whereupon the rack bars 95 43 can be moved by the springs 47 so that the top of the racks will come on to the end of the trigger 42.

What is claimed is:—

1. In a cash register, the combination of a 100 gate adapted to be moved rectilinearly; type wheels for printing the record or strip, and rack bars for operating said type wheels, the said rack bars being governed in the first portion of the stroke by the gate, and having 105 limited movement independent of the gate.

2. In a cash register, the combination of 110 rack bars; printing type wheels operated thereby; a hand operating part; a movable tappet device on said hand operated part for actuating said type wheels to effect their return stroke; a rectilinearly movable gate controlled by the action of the hand operated part, and operating in connection with the racks, so that the return stroke of the 115 rack bars is rendered greater than the return stroke of the gate, a holding and releasing pawl, and a spring by which the said bars are released from the tappet.

3. In a cash register a gate having rectilinear movement; type wheels; an inking roller operating in connection therewith; a gate releasing mechanism and mechanism for operating the type wheels, said mechanism being released by the gate releasing 125 mechanism, and having movement independent of the gate.

4. A cash register comprising sets of keys; a bodily rectilinearly movable gate controlled by the keys; spring actuated rack 130

bars which are released by the gate; a ticket marking and delivering mechanism having type wheels which are moved from the zero position to the position of action; an inking roller which inks the type wheels in their movement from the zero position to the position of action; so that in all cases the types will be inked before they act on the ticket to be printed on; substantially as herein set forth.

5. In a cash register, a rectilinearly movable gate, type wheels for printing the record, and means governed in part by the movement of the gate for operating the type wheels.

10. In a cash register, a rectilinearly movable gate, type wheels for printing the record, and means governed in part by the movement of the gate for operating the type wheels.

ord, and means governed in part by the initial portion of the movement of the gate for operating the type wheels.

20. 7. In a cash register, a rectilinearly movable gate, type wheels for printing the record, and means governed in part by the movement of the gate for operating the type wheels, the said means having limited movement independently of the gate.

25. In testimony whereof we have signed our names to this specification in the presence of two subscribing witnesses.

GEORGE MACBETH.
MALCOLM MACBETH.
